UNITED STATES PATENT OFFICE.

HENRY P. CLAUSEN, OF MAMARONECK, NEW YORK, ASSIGNOR TO WESTERN ELECTRIC COMPANY, INCORPORATED, OF NEW YORK, N. Y., A CORPORATION OF NEW YORK.

PHONOGRAPHIC APPARATUS.

Application filed February 3, 1920. Serial No. 356,052.

To all whom it may concern:

Be it known that I, HENRY P. CLAUSEN, a citizen of the United States, residing at Mamaroneck, in the county of Westchester, 5 State of New York, have invented certain new and useful Improvements in Phonographic Apparatus, of which the following is a full, clear, concise, and exact description.

10 This invention relates to phonographic apparatus and the object of the invention is the improvement of the apparatus to prevent the irregular vibrations of the moving systems in the recording or reproducing machines from being communicated to the operating or operated member, according to whether the device is for recording or reproducing.

In general, the invention provides for 20 mounting the operating or operated member, such as a diaphragm, spaced from the stylus, and directly connecting it thereto by a longitudinally movable member instead of the usual lever system. Specifically, the invention 25 provided for directly connecting the operating or operated member to the stylus when these elements are in spaced relation, by means of a longitudinally curved element, preferably a wire which is relatively 30 inflexible longitudinally and relatively flexible transversely but restrained from vibrating transversely by energy absorbing material engaging its sides.

In accordance with another feature, the 35 invention provides a single reproducer coupled to a plurality of styli and records for combining the reproductions from a plurality of records.

Referring to the drawings, Fig. 1 is a 40 side elevation partially in section, of one form of the invention as applied to a reproducer for use with a "hill and valley" type of phonographic record; Fig. 2 is a plan view of a reproducer for use with a 45 "transversely grooved" type of record; Fig. 3 is a cross section of a reproducer in which a plurality of sound boxes are operated by a common translating member; Fig. 4 is a side elevation partially in section, of a form 50 of the invention in which two separate records can be reproduced simultaneously through the medium of a single reproducing sound box common to the two records; Fig. 5 shows a form of the invention designed to 55 telephonically reproduce the matter record-

ed; Fig. 6 is a rear elevation of a reproducer for use with both "hill and valley" and "transversely grooved" types of record; Fig. 7 is a detailed side elevation thereof showing the method of supporting the stylus and 60 translating members extending from the stylus to the respective sound boxes; and Fig. 8 is a sectional view in perspective of the means used for translating movement between the stylus and the diaphragm of the 65 sound boxes.

In a form shown in Fig. 1, the stylus 9 rests upon a disc record 10 of the "hill and valley" type, which during rotation imparts a vertical movement to the stylus 9 corresponding to the sound trace present on the record. A sound box 11 having a diaphragm 12, is firmly mounted upon a supporting post 13, carried by a base 14. A translating member 15 is secured at its upper end to the 75 diaphragm 12 and at its lower end to a stylus holder 16, which in turn carries the stylus 9. The stylus holder 16 is constructed so that the stylus 9 can be readily removed therefrom and a new stylus substituted therefor when desired.

In phonographic apparatus the design requirements are such that the axis of the stylus and the axis of the sound box diaphragm are generally out of alignment with 80 one another and this relationship has heretofore required quite complex lever systems to translate movement between the stylus and the diaphragm. The necessity of these complex lever systems is, however, overcome 85 in the present case by forming the translating member 15 of such material and cross section as to be relatively inflexible longitudinally while relatively flexible transversely, and wire is particularly suitable for 90 this member. The upper end of the member 15 is substantially co-axial with the diaphragm 12 and the lower end is substantially co-axial with the direction of the movement of stylus 9, while the intermediate 95 portion is provided with one or more easy curves merging into the end portions to efficiently transmit vibrations between the stylus and diaphragm by longitudinal movements of the member 15. The member 100 15, except for its extreme ends, is enclosed within and closely engaged by a tubular casting 17 of energy-absorbing material, preferably soft rubber, which serves to resist and 105 to dissipate transverse vibrations of the 110

member. The casing 17 is in turn closely confined by an outer tube 18 which has a suitable amount of flexibility.

The upper end of the tube 18 is secured 5 to the upper part 19 of the post 13, which part has an opening therethrough in which a portion of the casing 17 is located and through which the member 15 extends. The lower end of the tube 18 is similarly secured 10 to a supporting arm 20, having an opening in which the lower end of the casing 17 is positioned and through which the lower end of the member 15 extends. This arm is pivoted on the base 14 for vertical 15 movement relative thereto and is of sufficient weight to hold the stylus 9 in proper engagement with the record 10.

With this construction the member 15 is so confined that vertical movement in the 20 stylus 9 effects corresponding longitudinal movement of this member and like vibrations of the diaphragm 12, to reproduce sound corresponding to those recorded on the record 10. This construction in addition tends to 25 resist and to dissipate such vibrations as may be set up in the member 15 in a direction transversely thereto and thus tends to prevent such vibrations reaching the diaphragm 12 and thus prevents unintended 30 vibration of the diaphragm with consequent distortion of the recorded matter being reproduced thereby. The sound produced by the sound box 11 may be distributed in any desired manner, a horn 21 being 35 shown in the drawing for this purpose, although obviously a multiple reproducer as shown in Fig. 3, may also be used if preferred. To enable the stylus 9 to accommodate itself to the varying distances of 40 the record trace from the axis of rotation of the disc record 10 as the latter is operated, the base 14 is vertically pivoted upon a supporting plate 22.

By utilizing a recording stylus in place of 45 the reproducing stylus 9, the construction shown in Fig. 1 can be used equally well as a recorder, the member 15 in this case effecting longitudinal movement of the recording stylus corresponding to the axial 50 vibrations of the diaphragm 12, while the casing 17 and tube 18 will act to resist and dissipate transverse vibrations of the member 15, as previously explained.

The form shown in Fig. 2, which is suitable 55 for "transversely grooved" types of phonographic records, differs from that shown in Fig. 1, by arranging the lower end of the translating member 25 with its corresponding casing 17 and tube 18 so as to 60 extend transversely of the record 26 instead of vertically thereof. The stylus holder 27 is fixed to this end of the member 25 to receive a stylus 28 positioned below the stylus holder 27 as shown in Fig. 2; this stylus being removable and arranged substantially

vertically relative to the record 26. In this form of reproducer transverse movements of the stylus effect corresponding longitudinal movements of the translating member 25 and corresponding actuation of the diaphragm of the sound box 12 to produce sounds corresponding to those recorded on the record 26. By using a recording stylus with the device shown in Fig. 2, it can be utilized for the making of 75 "transversely grooved" records.

The construction shown in Fig. 3 employs a plurality of sound boxes 30, 31 and 32, having respective diaphragms 33, 34 and 35 and respective horns 36, 37 and 38. The diaphragms are all connected to a common translating member 39 corresponding to the members 15 and 25 shown in Figs. 1 and 2 respectively. The diaphragms are co-axial and while the sound boxes 31 and 32 with 80 their respective horns 37 and 38 may be supported in any desired manner, in the form shown, this is accomplished by supporting the sound box 31 and its horn 37 from the horn 36, and the sound box 32 with its 85 horn 38 from the horn 37. This multiple sound box arrangement is particularly suitable where it is desired to have a large volume of sound reproduced, inasmuch as longitudinal movements of the member 39 90 in response to actuation of its reproducing stylus (not shown) effects movement of the diaphragms of all three sound boxes to reproduce the matter recorded, and results in the production of an aggregate volume of 95 sound representing the sum of that produced by the respective sound boxes 30, 31 and 32. The translating member 39 is provided with a casing 17 of energy absorbing material and an outer tube 18 for the purpose previously 100 described in connection with the form shown in Figs. 1 and 2.

The same construction can be utilized for recording in which case each of the diaphragms 33, 34 and 35 will be actuated by 110 the sound waves to be recorded and produce an increased movement of the member 39 over that produced by a single diaphragm. This provides a greater cut upon the record and is especially desirable where the original 115 sounds to be recorded are of small volume, or where it is desirable to provide a record which will reproduce a greater volume of sound than a record having the usual size 120 of record cut.

In the form of a reproducer shown in Fig. 4, two records 50 and 51 of the "hill and valley" type are shown and are designed to be operated in synchronism in any desired manner; like driven gears 52 and 53 and like driving gears 54 and 55, carried by a common driving shaft 56 being shown in the drawing for the purpose. Assume that it is desired to reproduce a violin and piano duet from two separate records, 125 130

on one of which only the violin part is recorded and on the other part of which only the piano is recorded. In the ordinary production of such records, the violin and piano players would play the duet together and separate synchronous records would be made of the violin and piano parts in any suitable manner; one such method being disclosed in a co-pending patent application of Harry B. Weir, Serial No. 317,410, filed August 14, 1919. A mark may be made on each record to enable the proper positioning of the respective records, relative to its respective reproducing stylus so as to reproduce the corresponding parts of the duet in proper time relation with one another.

A reproducing stylus 57 engages with the record 50 and is connected by a translating member 58 such as shown in Fig. 1, to the center portion of a reproducing diaphragm 59 of a sound box 60 having a horn 61. A like reproducing stylus 62 is similarly connected to the diaphragm 59 by another translating member 63. The translating member 58 is confined in and engaged by an enclosing casing 64 of energy-absorbing material and the member 63 by a like casing 65; and these casings are in turn surrounded by outer tubes 66 and 67 respectively, corresponding to the tube 18, illustrated in Fig. 1. A post 68 supports the sound box 60 and the forward ends of the casings 64 and 65, and of the tubes 66 and 67; while respective supporting arms 70 and 71 are secured to the opposite ends of these casings and tubes. The arms 70 and 71 are pivoted to a second post 72 which is mounted together with the post 68 upon a base 73 pivoted to a supporting plate 74.

In operation the two records 50 and 51 are each properly positioned relative to its reproducing stylus and the phonograph is set in operation. The records move in synchronism and movements of the stylus 57 by its record 50 effect corresponding longitudinal movements of the member 58 which in turn operates the diaphragm 59, while movements of the stylus 62 by its record 51, effect corresponding longitudinal movements of the member 63 which in turn also operates the diaphragm 59. Assuming that the record 50 is that of the violin part and that the record 51 is the piano part of the duet, movement of the diaphragm 59 by the member 58 tends to reproduce sound waves corresponding to those originally produced by the violin, and the movement of the diaphragm 59 by the member 63 tends to reproduce sound waves corresponding to those originally produced by the piano, so that the two members operating together effect a resultant movement of the diaphragm 59 such as to produce sound waves representing the combined violin and

piano parts and giving the effect of a violin and piano duet. The vibration of the diaphragm 59 due to the combined action of the members 58 and 63 is similar to the vibration which takes place by the diaphragm of a recording sound box when subjected to the combined action of sound waves from both a violin and a piano when playing a duet together. In order that the reproduction may be effected with the least possible distortion, it is advisable to provide an initial pressure on the diaphragm as in the case of the ordinary reproducers. This may be accomplished by making the pivoted arms 70 and 71 of sufficient weight to insure that each stylus is held in contact with its record regardless of the frequency or amplitude of the vibrations of the other stylus.

The form shown in Fig. 5 corresponds with that shown in Fig. 1, except that movement of the member 15 instead of operating the diaphragm of the sound box to reproduce the recording matter directly as sound waves, effects corresponding movement of the front electrode 80 of a variable resistance element 81 to produce corresponding variations in an electrical circuit in which such unit is included. These electrical variations can in turn be translated into corresponding sound waves through the medium of a telephone receiver associated with the circuit including the variable resistance unit 81. This unit is mounted on a supporting post 82 carried by the base 14, which base is pivoted to the supporting plate 22, for reasons previously set forth.

The form of the invention illustrated in Figs. 6 and 7 is designed for use with either a "hill and valley" type or a "transversely grooved" type of record and employs two sound boxes 85 and 86, one of which is operated when the reproducer is used with "hill and valley" type records and the other of which is operated when the reproducer is used with "transversely grooved" type records. The sound boxes are both mounted on a common supporting post 87 having a base 88 vertically pivoted to a supporting plate 89. An arm 90 is pivoted at one end of the post 87 so as to be vertically movable. A stylus 91 is provided and removably held in place within a stylus holder 92. The lower end of a translating member 93 is secured to the top of the holder 92, while the upper end of the member is secured to the diaphragm (not shown) of the sound box 85. The intermediate portion of the member 93 is enclosed within a casing 94 of energy-absorbing material which is in turn surrounded by a tube 95. The lower end of the translating member 96 is secured to the side of the stylus holder 92 and the upper end is secured to the diaphragm (not shown) of the sound box 86. The member 96 also has a casing 97 and tube 130

98 substantially identical with the casing 94 and tube 95 of the member 93. The member 93 with its casing 94 and tube 95 corresponds in construction and operation with the parts 5 15, 17 and 18 as shown in Figs. 1 and 8; while the member 96 with its casing 97 and tube 98 are the same in construction and operation as the parts 25, 17 and 18 as shown in Fig. 2. An L-shaped bracket 99 is pivoted 10 for vertical rotation on the arm 90, and the lower end of the casing 94 and tube 95 is secured to one arm of this bracket, while the lower end of the casing 97 and tube 98 is similarly secured to the other arm of the 15 bracket as shown in Fig. 6. The stylus 91 is preferably arranged so as to be substantially perpendicular to the plane of the record 100 in order to operate to best advantage with both types of record mentioned. 20 The weight of the arm 90 and the bracket 99 are such as to hold the stylus 91 in proper engagement with the record during operation.

In operation, assuming that the record 100 25 is of the "hill and valley" type, the stylus 91 is moved vertically and transmits longitudinal movement to the member 93 which correspondingly actuates the diaphragm of the sound box 85 to reproduce the sounds 30 recorded on the record 100. The vertical movement of the stylus 91 produces some transverse movement of the member 96 but the transverse vibrations of this member are absorbed by the casing 97 so that the dia- 35 phragm of the sound box 86 is not substantially effected. When the device is used with a "transversely grooved" type of record however, movements of the stylus 91 while transverse of the record produce like longitudinal movements of the member 96 and the development of corresponding sound waves by the diaphragm of the sound box 86 agreeing with the sounds recorded on the record. Such transverse movement of the 40 stylus while setting up transverse vibrations of the member 93 is without substantial effect on the diaphragm of the sound box 85, inasmuch as such transverse vibrations of the member 93 are practically eliminated by 45 the action of the casing 94 of energy-absorbing material engaging such member. 50

Obviously by using a recording stylus in place of a reproducing stylus 91, the device shown in Figs. 6 and 7 can be used for the 55 reproduction of both types of records mentioned; the sound box 85 being used if "hill and valley" type records are desired, and the sound box 86 being used if it is desired to make records of the "transversely grooved" 60 type.

What is claimed is:

1. A phonographic device comprising a phonographic record, a stylus to engage therewith, a movable member spaced from the stylus, a longitudinally curved element

relatively inflexible longitudinally but relatively flexible transversely extending longitudinally between and mechanically associated with the stylus and the movable member to translate movement therebetween, and a member of energy-absorbing material engaging the side of the element to resist transverse vibrations of the element. 70

2. A phonographic device comprising a phonographic record, a stylus to engage therewith, a movable member spaced from the stylus, a longitudinally curved wire relatively inflexible longitudinally but relatively flexible transversely extending longitudinally between and mechanically associated with the stylus and the movable member to translate movement therebetween, and a member of energy-absorbing material engaging the side of the wire to resist transverse vibrations of the wire. 80

3. A phonographic device comprising a phonographic record, a stylus to engage therewith, a movable member spaced from the stylus, a longitudinally curved element relatively inflexible longitudinally but relatively flexible transversely extending longitudinally between and mechanically associated with the stylus and the movable member to translate movement therebetween, a longitudinally curved casing spaced 90 from and enclosing the element, and a member of energy-absorbing material intermediate the element and casing engaging the side of the element and the interior of the casing to resist transverse vibrations of the 100 element. 90

4. A phonographic device comprising a phonographic record, a stylus to engage therewith, a movable member spaced from the stylus, a longitudinally curved element relatively inflexible longitudinally but relatively flexible transversely extending longitudinally between and mechanically associated with the stylus and the movable member to translate movement therebetween, a longitudinally curved tubular casing spaced from and enclosing the element, and a tubular member of absorbing material surrounding the element and engaging the element and the casing to resist transverse 110 vibrations of the element. 110

5. A phonographic device comprising a phonographic record, a stylus to engage therewith, a movable member spaced from the stylus, a longitudinally curved element extending longitudinally between and mechanically associated with the stylus and the movable member to translate movement therebetween, and a longitudinally curved tube enclosing the element to guide the movements of such element and within which the latter is longitudinally movable. 120

6. A phonographic device comprising a plurality of separate records, a stylus individual to each of the records, a reproducing 125

- element common to the plurality of records to effect a combined reproduction of the matter recorded on the separate records, a translating element individual to each of the styli and mechanically associating its respective stylus with the common reproducing element, and means to effect relative reproducing movement between the records and their respective styli. 15
- 10 7. A phonographic device comprising a plurality of separate synchronously recorded complimentary records, a stylus individual to each of the records, means to effect simultaneous and synchronous repro-
ducing movement of all the records, a reproducing diaphragm common to the plurality of records to effect a combined reproduction of the matter recorded on the separate complementary records, and a translating element individual to each of the styli and 20 mechanically associating its respective stylus with the diaphragm to translate movement between its respective stylus and the diaphragm. 25

In witness whereof, I hereunto subscribe my name this 28th day of January A. D., 1920.

HENRY P. CLAUSEN.
